CLAIM

The ornamental design of an implement handle, as shown and described.

DESCRIPTION

FIG. 1 is a perspective view of an implement handle showing our new design;

FIG. 2 is a rear view thereof;

FIG. 3 is a front view thereof;

FIG. 4 is a first side view thereof;

FIG. 5 is a second side view thereof;

FIG. 6 is a top plan view thereof;

FIG. 7 is a bottom plan view thereof;

FIG. 8 is a perspective view thereof shown in environmental use;

FIG. 9 is a perspective view thereof shown in a second environmental use; and,

FIG. 10 is a perspective view thereof shown in a third environmental use.

(Continued)

The features shown in broken lines in the drawing figures depict environmental subject matter only and form no part of the claimed design.

1 Claim, 7 Drawing Sheets
